DESIGN.

S. S. SCHIFF.

SOUND REPRODUCER FOR PHONOGRAPH OR SIMILAR DEVICE.

APPLICATION FILED OCT. 16, 1919.

55,333.

Patented May 25, 1920.

Inventor:
Samuel S. Schiff

By J. J. Jochum Jr. Atty.

UNITED STATES PATENT OFFICE.

SAMUEL S. SCHIFF, OF CHICAGO, ILLINOIS, ASSIGNOR TO VITANOLA TALKING MACHINE CO., A CORPORATION OF ILLINOIS.

DESIGN FOR A SOUND-REPRODUCER FOR A PHONOGRAPH OR SIMILAR DEVICE.

55,333.

Specification for Design.

Patented May 25, 1920.

Application filed October 16, 1919. Serial No. 331,185. Term of patent 7 years.

To all whom it may concern:

Be it known that I, SAMUEL S. SCHIFF, a citizen of the United States, residing at Chicago, in the county of Cook and State of Illinois, have invented a new, original, and ornamental Design for a Sound-Reproducer for Phonograph or Similar Device, of which the following is a specification, reference being had to the accompanying drawing, forming part thereof.

The figure is a view of a sound reproducer for phonograph or similar device, showing my new design.

I claim—

The ornamental design for a sound reproducer for phonograph or similar device, as shown.

SAMUEL S. SCHIFF.
